UNITED STATES PATENT OFFICE.

CHARLES F. P. ANDERS, OF HOBOKEN, NEW JERSEY, ASSIGNOR, BY DIRECT AND MESNE ASSIGNMENTS, TO EUGENE L. GREENEWALD, OF WASHINGTON, DISTRICT OF COLUMBIA.

VACUUM-BOTTLE.

1,172,248.

Specification of Letters Patent. Patented Feb. 22, 1916.

Application filed December 2, 1910, Serial No. 595,324. Renewed January 24, 1914. Serial No. 814,236.

To all whom it may concern:

Be it known that I, CHARLES F. P. ANDERS, a subject of the Emperor of Germany, and resident of Hoboken, in the 5 county of Hudson and State of New Jersey, have invented certain new and useful Improvements in Vacuum-Bottles, of which the following is a specification.

This invention relates to what are known 10 as vacuum bottles and in the particular form shown, it has reference to such bottles having therein two receptacles so that it may hold two separate things. It is of course the purpose of such bottles to maintain the 15 contents at the same temperature whether hot or cold and to prevent the passage of heat from the bottle to the outside atmosphere or the heat from the atmosphere to the contents of the bottle.

20 It has been my object to produce a bottle which can be easily and cheaply made and in which the parts will be firmly supported and at the same time the contents will be more effectively protected against changes 25 of temperature.

The novel features of the invention will be apparent from the following description taken in connection with the accompanying drawings.

30 In the drawings, Figure 1 is a longitudinal section through a device embodying the main features of my invention; Figs. 2, 3 and 4 are sectional views of the portion of a bottle showing modified forms of supporting and insulating means; and Fig. 5 is a detail perspective view of one form of supporting frame which may be used in my device.

As will be seen by reference to Fig. 1, the 40 outer wall 1 is preferably made cylindrical in form having the reduced or contracted upper end or neck 2, and it will of course be understood that this wall is made of glass. An inner receptacle 3 somewhat 45 smaller in diameter than the wall is inserted through the lower end 4 and its reduced or contracted neck 5 is fused to the outer edge of the neck 2, so that the inner receptacle and outer wall are integrally 50 connected at the lip or mouth and are separated at all other points by a vacuum space. The lower end 6 of the inner receptacle is tapered as shown for the purpose hereafter described. A second inner receptacle 7 of 55 slightly smaller diameter than the outer

wall is inserted through the open end 4 and it has the enlarged neck 8 which is fused at its edge to the lower edge of the outer wall so as to make the inner receptacle in one piece with the outer wall. This second inner receptacle has a tapered lower end 9 and before it is placed in position as above described, I place within the outer wall and over the end 6 of the inner receptacle 3 a centering, spacing and heat insulating device such as shown in the drawings, the tapered end 9 of the receptacle 7 fitting into one side of this device and the tapered end 6 fitting into the other side. This device serves to support and center the two inner 60 receptacles and this strengthens the device as a whole and prevents breakage, but it is so constructed and arranged that it will practically conduct no heat from the inner receptacle to the outer wall or from one inner receptacle to the other. The neck 5 of the upper inner receptacle is closed by a stopper 10 having the upper wall 11 and the lower wall 12 leaving a vacuum space between for the purpose of insulation. The 65 lower neck 8 has therein a closure 13 having the outer wall 14 and the inner wall 15, leaving a vacuum space whereby the contents of the inner receptacle is protected from changes in temperature outside of the 70 receptacle. At the point 16 there is an opening in the outer wall during the operations above described in the manufacture of the device, but after the inner receptacles and outer wall are in place and fused together in one integral whole the air surrounding the inner receptacles is exhausted through this opening and it is then sealed as shown so as to maintain the 75 vacuum.

The spacing and centering device as shown in Fig. 1 consists of two duplicate frames 17, 18, having the spider legs 19, 20. The spider legs or resilient arms extend from the central ring like portions at an angle downwardly and outwardly to the outer wall 1, the ends of the legs being curved upwardly as shown so as to give a flexible connection or yielding contact with the outer wall. The bends in the legs 19 and 20 providing feet which rest upon opposite sides of a mica disk 21 which fits within the outer wall and which by reason of the fact that it is a poor conductor of heat will serve as an insulation. The central 80 85 90 95 100 105 110

ring like portions of the two frames 17 and 18 have at their inner edge the short lugs 22, 23 at intervals, and at their outer edge they have longer integral upwardly projecting bent parts or lugs 24, 25. Flat ring like disks 26, 27 of mica rest on the lugs 22, 23 and bear at their outer edge against the lugs 24, 25 and as shown the central opening in these mica plates is smaller than the openings in the metal frames. The tapered ends 6 and 9 of the inner receptacles bear on the inner edges of these mica rings and thus the mica rings serve as an insulation preventing the passage of heat between the inner receptacles and the outer wall. The flexible or resilient nature of the parts, furthermore, serves to furnish a yielding support and centering device for both the inner receptacles, holding them securely in position and preventing breakage due to jars. It will be understood that these parts of the device are inserted after the inner receptacle 3 has been secured in place and before the inner receptacle 7 is inserted.

In Fig. 2, I have shown a coil spring 28 which is inserted between the inner pointed ends of the inner receptacles and it serves to support and center those receptacles and at the same time furnishes little opportunity for the passage of heat from one to the other. This form of yielding connection between the parts may be used in place of that described in connection with Fig. 1, but I prefer that shown in Fig. 1.

In Fig. 3, I have shown another modified form of means for supporting and centering the two inner receptacles and in this instance, I make use of an upper frame 29 having radial arms or legs 30 extending at an angle out to the outer wall 1 and on this frame I support the mica disk 31 in the way described in connection with Fig. 1 surrounding the end 6 of the inner receptacle. A second frame 32 carries a mica disk 33 surrounding the end 9 of the inner receptacle and having the curved radial legs 34, which legs have at their outer ends notches so as to make them embrace the legs 30 of the other frame as is shown clearly in Fig. 5. The two frames in this form are therefore flexibly or yieldingly supported from each other and are also supported from the outer wall so as to properly center and support the inner receptacle or receptacles.

In Fig. 4, I have shown a modified construction similar to that shown in Fig. 3 with the exception that I have placed a flat circular disk of fibrous material 35 over the mica disk 31, and the inner receptacle rests against this disk made of fiber. A similar disk 36 is placed on the lower frame on the mica disk 33 and this forms a still more effective means for insulating the inner receptacles to prevent the passage of heat be-

tween those receptacles and the outer atmosphere.

It will be understood that one or more disks may be used in each of the forms disclosed for supporting the inner receptacles and that various modifications in the structure may be made without departing from my invention.

It is to be understood that in this application a "wide-mouth" inner or outer member means an inner or outer member which has a mouth substantially as great in diameter as the body of the member, and that a "narrow-mouth" inner or outer member means an inner or outer member which has a mouth considerably smaller in diameter than the body of said member.

Having thus described my invention, what is claimed is:

1. A vacuum bottle comprising an outer wall and two receptacles fitting therein from opposite ends of the wall, said receptacles being separated from the wall by a vacuum space.

2. A vacuum bottle comprising a tubular outer wall open at both ends, two receptacles fitting in said ends secured thereto and spaced from said outer wall, closures for said inner receptacles, and means for supporting the inner ends of said receptacles within said outer wall.

3. A vacuum bottle comprising a single outer wall and two opposed inner receptacles spaced from said wall, and yielding means between the inner ends of said inner receptacles for spacing and supporting said receptacles within the outer wall.

4. A vacuum bottle comprising a tubular outer wall open at both ends, two inner receptacles fitting in said ends and spaced from said outer wall, the ends of said inner receptacles and wall being secured together forming open necks for the inner receptacles, closures for said necks, and yielding means for supporting the inner ends of said receptacles within said outer wall.

5. A vacuum bottle comprising a tubular outer wall open at both ends, one of said openings being as great as the diameter of said tubular wall, two inner spaced receptacles fitting in said outer wall at the opposite ends and secured thereto at the ends, and means independent of the outer wall for supporting the inner ends of said receptacles.

6. A vacuum bottle comprising a tubular outer wall open at both ends, one of said openings being contracted and the other being as great as the diameter of said tubular wall, an inner receptacle spaced from said outer wall and having a contracted neck secured to said contracted end, and another inner receptacle in line with the first having its neck secured to the larger end of said outer wall.

7. A vacuum bottle comprising a tubular outer wall open at both ends, one of said openings being contracted and the other being as great as the diameter of said tubular wall, an inner receptacle spaced from said outer wall and having a contracted neck secured to said contracted end, and another inner receptacle in line with the first having its neck secured to the larger end of said outer wall, the two inner receptacles having separated tapering inner ends and yielding separating and supporting means between said ends.

8. A vacuum bottle comprising a single tubular outer wall, two inner oppositely facing receptacles therein in line and spaced therefrom, the said inner receptacles having separated tapering inner ends, and yielding supporting means interposed between the ends of said inner receptacles and bearing upon the inner surface of said outer wall.

9. A vacuum bottle comprising outer and inner spaced members, the inner member having a tapering end, a frame bearing at different points against the inner surface of said outer member and provided with a central opening, and a heat insulating device carried by said frame over said opening and fitting said tapered end to support said inner member.

10. A vacuum bottle comprising outer and inner spaced members, the inner member having a tapering end, a frame having resilient arms with curved ends bearing against the inner surface of said outer member, and a heat insulating plate carried by said frame having a central opening fitting the tapering end of said inner member and serving as a support.

11. A vacuum bottle comprising outer and inner spaced members, the inner member having a tapering end, a frame having resilient arms with curved ends bearing against the inner surface of said outer member, and a central ring like portion having short upwardly extending lugs at its inner margin and longer upwardly extending lugs at its outer margin, and a flat disk like ring resting on said inner lugs and bearing against said outer lugs and having a central opening smaller than the opening in said frame fitting the tapered end of said inner member.

12. A vacuum bottle comprising a single tubular outer wall, two inner oppositely facing receptacles therein in line and spaced therefrom, the said inner receptacles having separated tapering inner ends, two separated frames each carrying a heat insulating ring fitting the tapered ends of said inner receptacles, and yielding connections tending to separate said frames and to center them within said outer wall.

13. A heat insulated container comprising a tubular outer wall and two receptacles

within said wall spaced therefrom and secured to said tubular wall at different ends thereof.

14. A glass heat-insulated bottle comprising an outer glass wall and two glass receptacles integrally united at their mouths to said outer wall and being otherwise separated from said outer wall by a vacuum space, and means between the receptacles and said outer wall for spacing and supporting the receptacles from said wall.

15. A double-walled vacuum insulated container comprising an outer wall, a receptacle within said wall, said receptacle being integrally connected to said wall at its mouth and being otherwise separated from said wall by a vacuum space, and means for spacing said receptacle from said wall, said means comprising a member of resilient material having a plurality of integral bent parts thereon, and heat insulating means associated with said member and engaged by said bent parts to hold said insulating means in place on the resilient member.

16. A vacuum bottle comprising an outer wall substantially cylindrical in shape below its neck, a receptacle spaced from the inner surface of said wall and having a tapering bottom, and means for yieldingly supporting said receptacle in said outer wall, said supporting means engaging the tapering bottom of said receptacle and having parts extending upwardly and into contact with the inner cylindrical surface of said outer wall.

17. A heat insulated container comprising an outer wall, a receptacle within said wall, said receptacle being connected to said wall at its mouth and being otherwise separated from said wall by a space, and means for supporting the inner end of said receptacle and spacing it from said wall comprising a yieldable member engaging the inner surface of said wall and having a flat surface, and a heat insulating member engaging said receptacle and having a flat surface opposite the flat surface of said yieldable member.

18. In a container, the combination of two receptacle members having mouths, and a wall inclosing both receptacles, said wall being joined to the mouth of each receptacle leaving said mouths open, said wall being otherwise spaced from the body of each receptacle a uniform distance entirely around the receptacle.

19. A container comprising a wide mouthed receptacle, a narrow mouthed receptacle, having a neck of smaller diameter than the body thereof, and a casing inclosing both receptacles, said casing having engagement with said receptacles near their mouths and spaced from the bodies thereof.

20. A double-walled vacuum insulated container comprising an outer wall, a receptacle within said wall, said receptacle

being integrally connected to said wall at its mouth and being otherwise separated from said wall by a vacuum space, and insulating and spacing means in the vacuum space between said receptacle and said wall comprising a resilient plate having a plurality of bent parts integral therewith which yieldingly press against said outer wall.

21. A container comprising two receptacle members, an inclosing casing for both said members, and yielding means located between the inner ends of said members and the inner surface of said casing for holding said members in place, and heat insulating means carried by said yielding means.

22. A vacuum insulated container comprising an inner receptacle member having a tapering bottom, an outer member inclosing said inner member and separated therefrom by a vacuum space, a device bearing against the inner surface of the outer member and provided with a recess, and a heat insulating member carried by said device and having a recess registering with the recess in said device and fitting said tapering bottom to support said inner receptacle and space it from the wall of the outer member.

23. A vacuum bottle comprising an inner receptacle member, an outer wall member united to the inner member at the top and otherwise spaced therefrom, and means for holding and insulating the body of the inner member apart from the body of the outer member, said means comprising a device having a central part provided with resilient arms yieldingly pressing toward the surface of one of the members, and a second device of heat-non-conducting material engaging one of said members and carried by the first mentioned device, said first mentioned device having spaced bent portions integral therewith and engaging the heat-non-conducting material to hold the latter in place.

24. A double walled vacuum insulated container comprising a receptacle member, an outer wall integrally united with said receptacle member and separated therefrom by a

vacuum space, and means for holding the lower end of the receptacle member apart from the outer member comprising a plate having a part engaging the inner surface of said outer wall and a second plate having a part engaging the receptacle member, one of said plates being of heat insulating material and one of said plates having means for holding the other plate in place and a plurality of integral resilient portions carrying said holding means.

25. A heat insulating device for double walled vessels comprising a resilient metal member and a ring of non-heat-conducting material associated therewith.

26. A container comprising a receptacle member, an outer member surrounding said receptacle member, and means holding the bottom of the receptacle member apart from the outer member comprising a frame carrying a part bearing against the end of the receptacle member and provided with downwardly extending arms having their ends bent upwardly and bearing against the inner surface of said outer member.

27. A heat insulating device for double walled vessels comprising a resilient plate having an opening therein and lugs thereon, and a heat insulating ring extending over the edge of said opening and held in place on said plate by said lugs.

28. A vacuum bottle comprising a receptacle member, an outer member surrounding said receptacle member, and means holding the bottom of the receptacle member apart from the outer member comprising a frame carrying a part fitting the bottom of the receptacle member and resilient arms extending from said part downwardly and then bent upwardly into engagement with the inner surface of said outer member, said arms being integral and the bends therein providing feet thereon.

In testimony whereof I affix my signature in presence of two witnesses.

CHARLES F. P. ANDERS.
